UNITED STATES PATENT OFFICE

141,779

DESIGN FOR A TOWEL RACK

David Greene, Brooklyn, N. Y., assignor to Esmco
Auto Products Corp., Brooklyn, N. Y., a corporation of New York

Application May 12, 1945, Serial No. 119,514

Term of patent 14 years

(Cl. D33—16)

To all whom it may concern:

Be it known that I, David Greene, a citizen of the United States, residing at Brooklyn, in the county of Kings and State of New York, have invented a new, original, and ornamental Design for Towel Racks, of which the following is a specification, reference being had to the accompanying drawing, forming part thereof.

The figure is a front perspective view of a towel rack showing my new design.

I claim:

The ornamental design for a towel rack, as shown.

DAVID GREENE.
